UNITED STATES PATENT OFFICE

JULES SCHWAB, OF NEW YORK, N. Y.

DESIGN FOR A BRACELET

Application filed January 24, 1931. Serial No. 38,443. Term of patent 7 years.

To all whom it may concern:

Be it known that I, JULES SCHWAB, a citizen of the United States, residing at New York, in the county of New York and State of New York, have invented a new, original and ornamental Design for a Bracelet, of which the following is a specification, reference being had to the accompanying drawing, forming a part thereof.

In the drawing:

I claim:

The ornamental design for a bracelet, as shown.

JULES SCHWAB.
